FORK OR SIMILAR ARTICLE OF FLATWARE

Tsuneo Murase, 15015 Gramercy Place, Apt. 3-C,
Gardena, Calif.

Filed May 12, 1964, Ser. No. 79,941

Term of patent 3½ years

(Cl. D54—12)

FIG. 1.

FIG. 2.

FIG. 3.

FIG. 4.

FIG. 5.

FIG. 1 is a top plan view of fork or other similar article of flatware showing my new design;

FIG. 2 is a bottom plan view thereof;

FIG. 3 is a side elevational view thereof;

FIG. 4 is a sectional view thereof on an enlarged scale, taken on the line 4—4 of FIG. 1; and,

FIG. 5 is a sectional view thereof on an enlarged scale, taken on the line 5—5 of FIG. 1.

I claim:

The ornamental design for a fork or other similar article of flatware, substantially as shown.
